UNITED STATES PATENT OFFICE.

JEFFERSON HENRY HAWTHORN, OF POWELL, TEXAS.

COTTON TRAMPER.

Application filed March 16, 1926. Serial No. 95,089.

This invention relates to cotton trampers and particularly to those trampers in which the plunger is operated by gearing from a power shaft as distinguished from those which are operated by pneumatic pressure.

The general object of the invention is to provide a trumper which is entirely automatic in its action and in which so long as it receives power the plunger is caused to alternately move downward and upward.

A further object is to provide for a proper operation of the cotton feeding means when the plunger is raised and to stop the operation of the feeding means when the plunger has been depressed a predetermined degree, and another object in this connection is to provide means for automatically applying a brake to the shaft carrying the feeding blades to thereby prevent this shaft from overrunning after the plunger has reached a predetermined position.

Other objects will appear in the course of the following description.

My invention is illustrated in the accompanying drawings wherein:—

Figure 1 is a top plan view partly in section of a cotton trumper constructed in accordance with my invention;

Figure 2 is a vertical sectional view on the line 2—2 of Figure 1;

Figure 3 is a side elevation of the band wheel and cam;

Figure 4 is a section on the line 4—4 of Figure 1;

Figure 5 is a section on the line 5—5 of Figure 1; and

Figure 6 is an elevation of the driving gear wheel for the plunger.

Referring to the drawings it will be seen that the frame of the machine comprises the longitudinally extending beams 10, transverse end beams 11, the vertical supports 12, the lower longitudinal beams 13, and certain cross beams, later referred to.

At one end of the frame and between one of the end beams 11 and the cross beam 14, I provide the two vertically extending guides 15, each guide being formed to provide a guide groove 16. These guide members 15 are suitably spaced from each other, and operating between these guide members is the plunger, comprising the base or plate 17 and the plunger rods 18, spaced from each other and connected by the cross pins 19, these pins 19 constituting a rack to which the plunger proper is attached. The upper

ends of the rods are connected by means of a transverse brace 20 which operates within the groove 16, this brace carrying the slides 21 bearing against the walls of the groove 16 so that the plunger may operate easily.

Operating upon the pins 19 and acting to raise or lower the plunger is a gear wheel 22 mounted upon a shaft 23. This shaft is mounted in suitable bearings upon the longitudinal beams 10 and carries at its ends the sprocket wheels 24. Extending parallel to the shaft 23 is a shaft 25 which carries at its extremities sprocket wheels 26, which are relatively smaller than the sprocket wheels 24 and engaging these two sprocket wheels 24 and 26 are the sprocket chains 27. Mounted upon the shaft 25 are the two oppositely disposed spaced beveled gear wheels 28 and 28^a.

Disposed in suitable bearings upon one of the end beams 11 and the transverse supporting beam 29, or otherwise suitably mounted, is a shaft 30 carrying upon it a beveled gear wheel 31 having interrupted teeth. Specifically this beveled gear wheel has teeth upon slightly less than one half of its periphery, the remainder of the periphery being bare of teeth so that as the beveled gear wheel rotates with the shaft 30, the teeth 32 will alternately engage with one or the other of the beveled gears 28 and 28^a and obviously the shaft 25 will be driven alternately in opposite directions by a continuous rotation of the bevel gear wheel 31 in one direction. The shaft 30 carries upon it the fast and loose pulleys 33 and 34 and a belt 35 transmits power from any suitable power shaft to these pulleys and this belt is shifted onto the fast or loose pulleys, as desired, by means of a belt shifter 36 which is slidably mounted on the frame of the machine and is operated by means of a lever 37.

For the purpose of feeding the cotton to the box beneath the plunger I provide a chute including the upper and lower downwardly inclined walls 38, and extending beneath these walls is the shaft 39 which carries upon it the diametrically disposed blades 40 which, as this shaft 39 is rotated, act to feed the cotton downward through the chute into the press box but which when the shaft is shifted to a position where the blades are vertical, prevents the discharge of cotton into the press box. For the purpose of operating this shaft 39 I provide the

shaft at one end with a gear wheel 40^a meshing with a gear wheel 41, mounted upon a longitudinally extending shaft 42 which, of course, extends parallel to the shaft 30 and is supported in suitable bearings in the frame of the machine. This shaft carries upon it the fast and loose pulleys 43 and 44 and mounted upon the shaft 30 is a band wheel 45 from which a belt 46 passes to the fast or loose pulleys 43 and 44. It is necessary that this belt 46 be automatically shifted to the loose pulley when the plunger has descended to a predetermined point to thereby stop the rotation of the feeding blades and hold the blades in position to prevent the further descent of cotton into the press box. To this end I mount beneath the band wheel 45 a belt shifter consisting preferably, though not necessarily, of a metal plate 47 pivoted at its rear end, as at 48, upon one of the beams 10 and at its forward or free end having upturned flanges 49 which engage with the belt 46. This plate 47 or belt shifter is provided upon its opposite margins with the upwardly extending flanges 50 and engageable alternately with these flanges are the cams 51 and 52. The forward ends of these cams are, of course, rounded and the cams are disposed in a transversely diametrical relation so that as the band wheel 45 rotates in the direction of the arrow in Figure 1, the cam 51 for instance, will strike the flange 50 on one side of the belt shifter 47 and will shift it in a direction to carry the belt 46 onto the fast pulley 43 and in a further rotation of the band wheel the cam 52 will act to shift the belt shifter in the other direction to carry the belt 46 onto the loose pulley 44. Obviously when the belt has thus been shifted, power will be no longer transmitted to the shaft 42 and the feeding mechanism will come to a stop. Inasmuch as, however, this feeding mechanism would be likely to over-run I provide a brake for this shaft comprising a band 53, passing partially around a brake wheel 54 mounted upon the shaft 42, one end of this brake band 52 being connected to the frame of the machine below the pulley 54 while its other end passes over a cam 55 mounted upon the shaft 30. This end of the brake band is engaged by a contractile spring 56 which holds the brake band taut against the cam 55. At the moment when the trumper plunger has reached such position that no more cotton is to be fed into the press beneath the plunger, the cam 55 is brought to a vertical position where it will tighten the brake band 53 to such an extent as to cause the immediate stoppage of the shaft 42 with the blades 40 in a vertical position which will block all passage of cotton into the press box.

65 The operation of this mechanism will be

obvious from what has gone before. At the time when the plunger has risen to its full extent, the gear teeth 33 have left the gear wheel 28 and simultaneously engaged the gear 29^a, thus causing a reverse rotation of the shaft 25 and through the sprocket wheels 27 causing a like rotation of the shaft 23 and the descent of the trumper. While the trumper is raised the fast pulley 43 has been engaged by the belt 46 with the shaft 30 and as a consequence, is operating to feed cotton into the press box through the chute 38. When the plunger has descended a predetermined amount, however, and passed beyond the chute 38 the cam 52 will operate to shift the lever 47 in a direction to carry the belt 46 onto the loose pulley thus, as before explained, cutting off power from the shaft 42 and from the feeding shaft 39. Just as this occurs, the cam 55 has reached a point where it tightens up on the brake band 53 thus applying the brake to the shaft 42 and preventing further movement of the shaft and holding the blades 40 into vertical position. They remain in this position until the plunger through the action of the gears 31 and 28 has risen a predetermined amount and at this time the cam 55 has rotated sufficiently to slacken the brake 53 and at the same time, the cam 51 acts to shift the wheel 47 in a direction to cause the belt 46 to shift onto the fast pulley 43 thus again operating the feeding mechanism.

It will be seen that this mechanism is entirely automatic in its action and that so long as power is applied to the shaft 30 the plunger will be intermittently raised and depressed and the feeding mechanism will be intermittently operated or stopped. The mechanism is very simple, can be relatively cheaply made, has no parts which are liable to get out of order, and may be made relatively light and thus it costs less to manufacture than the ordinary cotton trumper.

One of the particular advantages of the invention is that the packer is reversible so that it may work on either side of the press and may be thus disposed within the packing house at the most advantageous point. Thus, for instance, it is only necessary in order to change from one side of the press to the other to reverse the packer to transfer shaft 42 with pulleys 41, 43, 44 and 54 to the opposite side of frame or in other words to the bearing 42^a in Figure 4, then transfer the shaft 39 with pulleys 40^a and blade 40 to the bearing 39^a in Figure 4. To transpose the feeding mechanism, transpose the belt shifter 47 to the opposite side of the frame and, of course, the spring 56 and band 53 would be transposed also. The gear shifter 36 and the lever 37 should also be transposed to the opposite side of the frame. The cams 51 and 52 on pulley 45 are reversed in

their direction on the pulley 45 so as to operate the pulleys 47 and 44 in an opposite direction to what they formerly did and obviously the shaft 30 might operate in an opposite direction to what it formerly did. Thus, a few small changes can be made in my machine to place the operating or controlling mechanism on the opposite side of the press where in other trampers the entire machine must be changed. Obviously, the machine will be made as particularly shown in Figure 4 so as to permit these changes to be made.

It is to be particularly noted that the feeding mechanism of my trumper is operated by the same mechanism which in turn reciprocates the trumper. Thus, both the feeding mechanism and the tramping mechanism are operated by a single belt where heretofore two drive belts, one for the trumper and one for the feeder, have been used.

I claim:—

1. Mechanism of the character described including a driven shaft having loose and fast pulleys thereon, a drive shaft having a pulley thereon, a belt connecting the pulley on the drive shaft with the pulleys on the driven shaft, and means whereby to shift said belt from the loose pulley to the fast pulley and vice versa, including a pivotally mounted plate having upturned flanges at one end for engaging the belt, upwardly extending flanges on the plate adjacent the other end, and cams arranged upon opposite sides of the pulley on the drive shaft adapted to engage the second mentioned flanges on the plate for imparting lateral movement to said plate whereby to shift the belt from the loose to the fast pulley and vice versa.

2. Mechanism of the character described including a drive shaft, a driven shaft having loose and fast pulleys thereon, a pulley on the drive shaft, a belt connecting the pulleys on the drive and driven shafts, means for shifting said belt from the loose pulley to the fast pulley at a predetermined distance and returning the belt from the fast pulley to the loose pulley, a brake wheel upon the second shaft, a brake band extending over said brake wheel and having one end rigidly supported, a spring exerting tension upon the other end of the band, and a cam upon the drive shaft adapted to exert pressure upon the brake band when the belt is shifted from the fast pulley to the loose pulley, as and for the purpose set forth.

3. Mechanism of the character described including a driven shaft having fast and loose pulleys thereon, a drive shaft having a pulley thereon, a belt connecting the pulley on the drive shaft with the pulleys on the driven shaft, and means for automatically shifting said belt at intervals from the loose pulley to the fast pulley including a pivotally mounted member formed for engagement with the belt, and cams mounted on the drive shaft adapted to alternately engage the said pivoted member to impart lateral movement to said member alternately in opposite directions whereby to shift the belt from the loose to the fast pulley and vice versa.

In testimony whereof I hereunto affix my signature.
